UNITED STATES PATENT OFFICE.

FRANZ PUENING, OF PITTSBURGH, PENNSYLVANIA.

DISTILLING CARBONACEOUS MATERIAL.

Application filed November 8, 1922. Serial No. 599,179.

This invention relates to the art of distilling carbonaceous material, such as bituminous coal, lignite, shale, peat, or other carbonaceous material which forms coke.

- 5 An object of the invention is to provide an efficient furnace construction that permits the distillation of such carbonaceous material at low temperatures, in accordance with the principle of low temperature distillation disclosed in one embodiment in 10 my prior application for Letters Patent of the United States Serial No. 535,790, filed February 11, 1922, and in another embodiment in my prior application for Letters 15 Patent of the United States, filed February 11, 1922, Serial No. 535,791. This principle of low temperature distillation involves the bringing of the material to be distilled into direct contact with a solid heat transfer 20 medium previously heated to a temperature great enough to effect the entire distillation of the material by transfer thereto of part of the heat stored in the heat transfer medium.
- 25 In carrying out the distillation there are employed, as the medium for effecting the transfer of the distilling heat to the material to be distilled, heating walls of a substance of high enough heat conductivity to effect 30 a rapid transfer of the distilling heat to the material, for example, bituminous coal. For example, bricks may be employed, or, as in the present embodiment, metal heating walls, iron, in any one of its several forms, 35 being especially suitable because of its great specific weight, its high heat conductivity, its good wearing qualities, its resistance to deterioration when subjected to rapid temperature changes and the influence of hot 40 gases, and lastly, because of its cheapness. The invention, however, is not limited to the employment of iron as the material for the heating walls.

These heating walls are first exposed to the action of hot gases to store in them the heat which is subsequently employed for effecting the distillation of the material. Any hot gases may be employed, provided that they are not of such a nature as to readily injure the heating walls. In any case, the temperature to which the heating walls may be heated is limited by the resistance of the material of which they are composed to oxidize or be otherwise impaired at high temperatures. In case iron is employed, however, the walls may be

heated to a temperature of about 1400° F. in an atmosphere of well burned gases, without unduly exposing the iron to deterioration.

With iron heating walls heated to a surface temperature of 1400° F., distillation of the coal may be effected by bringing the coal into direct contact with such previously heated walls. The coal to be distilled may be either at ordinary atmospheric temperature, prior to the time of contact with the heating walls, or may be preheated, if desired. At the moment of contact, coal quickly absorbs the peak of the heat stored in the surface of the walls and in the portions of such walls just below its surface. The particles of the coal in contact with the heating walls are thus rapidly heated, the heat penetrating into the interior of the coal. During the heating up stage, a dry skin of coke is formed on the coal, thereby permitting ready separation of the coal from the walls at the completion of the distillation operation. As the heat transfer from the walls to the coal progresses, the flow of heat into the coal diminishes in rate, along with the approach of the coal and the heating walls into an equilibrium of temperature. In order to avoid an impractical slowing up of the heat transfer, after the initial rapid heat absorption by the coal, the weight of the heating walls, with respect to the coal being distilled, is regulated so that the storage capacity for heat of the walls is in excess of the heat required to bring the coal to the required final temperature. The final temperature varies, of course, with different coals and with the other materials available for treatment by the distillation process of the invention. For many of such materials, however, a satisfactory final temperature is approximately a thousand degrees F. and the process of low temperature distillation would be completed at that temperature. It requires about 400 B. t. u. per pound of material, in order to heat commercial grades of bituminous coal to a final temperature of a thousand degrees F. In order to attain such a final temperature, a maximum temperature drop of the heating walls from 1400° F. to a thousand degrees F. is available. Between 1400° F. and a thousand degrees F., iron, for example, has a specific heat of approximately 0.148. Therefore, $(1400-1000) \times 0.148 = 59$ B. t. u. are freed

for absorption by the coal, when one pound of iron drops from 1400° F. to a thousand degrees F. Inasmuch as 400 B. t. u. are required for one pound of coal, 400 divided by 59 equals 6.77 pounds of iron which are required to furnish sufficient heat for elevating one pound of coal to a final temperature of approximately 1,000° F. In order to compensate for the slowing down of the 10 heat transfer, as above explained, it is preferable to employ approximately twice as much iron as the theoretical minimum, which would be approximately 14 pounds of iron for each pound of coal to be distilled.

15 By preheating the coal or drying it before bringing the coal into contact with the hot iron, the amount of heat required for the distillation process may be materially reduced. This would permit the process to be 20 carried on with a smaller quantity of iron. Even when preheating of the coal is employed, it is preferable to employ enough iron in order that the heat available for distillation be about twice the amount of the 25 theoretical minimum.

An apparatus for practicing the above described low temperature distillation process and constructed in accordance with the invention has the following essential characteristics: The apparatus consists of a rectangular furnace built of fire clay bricks and provided with girders mounted over the top of the furnace from which the heating walls are hung. The heating walls project in 30 spaced relation into the furnace chamber which serves first as a heating chamber through which hot gases are circulated to heat the walls to the required coking temperature, and, secondly, as a space divided 35 by the heating walls into a plurality of distilling chambers or retorting spaces for receiving the carbonaceous material to be coked and holding it in heat transfer contact with the previously heated walls. Each 40 heating wall is preferably constituted of a separate unit provided with its individual hanger, but the several walls are collectively united by link means located at the top of the walls, the link construction permitting 45 the walls to be pulled apart slightly before pushing the coke, in order to avoid jamming or injury to the walls during the pushing operation and in order to break up any adhesions of material to the sides of the heating 50 walls before beginning the pushing operation. By this construction, the pushing of the coke is greatly facilitated. Side walls for closing the ends of the retorting spaces or coking spaces between the heating walls 55 are provided to prevent the material being distilled from falling out at the ends of the heating walls. These side walls are also hung from a girder at the top of the furnace in such manner that they may be pulled 60 away from the opposite ends of the heating 65 walls, before the latter are spaced, as just mentioned, for pushing. Consequently, any bond, which may have been formed between the side walls and the coke between the heating walls, will be broken, thereby permitting 70 the heating walls to move apart readily for the pushing operation. Bottom doors are provided to prevent the material being coked from falling into the discharging apparatus. After the heating operation has been completed, these bottom doors are closed but when the coke is ready to be pushed they are 75 opened, forming a chute to guide the coke as it discharges from the retorts between the heating walls.

In addition to the general objects recited above, the invention has for further objects such other improvements and advantages in operation and results as may be found to obtain in the processes or apparatus herein-after described or claimed.

In the accompanying drawings, forming a part of this specification, and showing for purposes of exemplification, a preferred form and manner in which the invention may be embodied and practiced, but without limiting the claimed invention to such illustrated instance or instances:

Figure 1 is a vertical section taken transversely through the heating walls and at one end of a low temperature distillation furnace constructed in accordance with the improvements of the invention.

Figure 2 is a vertical section similar to Fig. 1, but taken at the opposite end of the furnace.

Figure 3 is a vertical section of the furnace taken on the plane parallel with one of the heating walls and showing the latter in side elevation.

Figure 5 is an enlarged fragmentary vertical section illustrating the construction at the upper end of a heating wall and also showing a modified construction of another heating wall.

Figure 6 is a fragmentary plan and horizontal sectional view illustrating the spacer link construction at the ends of the heating walls.

Figure 7 is a vertical section taken on the line VII—VII of Fig. 6.

Figure 8 is a fragmentary side elevational view of the side wall construction.

Figure 9 is a vertical section taken on the line IX—IX of Fig. 8.

In its present embodiment, the invention is applied to the low temperature distillation of bituminous coal, for producing coherent coke, such as is available for domestic heating purposes. For convenience, the ensuing description will be confined to this application of the invention. The novel features and improvements of the invention are, how-

ever, applicable to the distillation of other carbonaceous material, for example, to any of the other materials hereinabove mentioned; hence, the scope of the invention is not confined to the specific use and specific embodiment herein described as an illustrative example.

Referring to the drawings: There is shown at A a chamber having surrounding walls B which may be constructed of fire clay brick, as previously mentioned, or of any other satisfactory refractory material. The chamber A serves first as a heating chamber in which hot gases are circulated to bring the heating walls 1 up to the required coking temperature, and, secondly, as the space in which are located the distilling retorting spaces between the previously heated walls. The heating walls 1 are constituted of elongated relatively thin vertical members having flat sides against which the material to be coked makes contact and preferably, although not necessarily, constructed of metallic brick sections, as shown. Refractory material may be employed in building up the heating walls, if desired, and the invention is not limited to the employment of metallic heating walls, such as mentioned above and in the descriptive matter explanatory of the low temperature distillation principle employed in the apparatus of the present invention. The wall sections or bricks of the respective walls 1 are hung on supporting rods 2 (Fig. 5), which supporting rods project somewhat above the tops of their respective heating walls and at their upper ends are secured by bolts or pin fastenings 4 to the horizontal beam assemblies 3, the latter being individual to the respective heating walls.

These beam assemblies extend parallel with their respective heating walls, and may be constructed in either of the two forms shown by way of example in Fig. 5. In one form, that shown at the right hand heating wall of Fig. 5, the beam assembly 3 is made up of a horizontal bar *a* provided at spaced intervals with sockets *b* to receive the upper ends of the supporting rods 2, and of a horizontal U-beam *c* the sides of which embrace the sides of the lower beam *a*. The top of the U-beam *c* is, however, spaced from the top of the connected lower beam *a* to provide a passage *p* through which stack gases or other cooling media may be circulated to keep the beam assembly cool. In the form of beam assembly construction employed in connection with the heating walls shown at the extreme left of Fig. 5, the beam is made up of a U-shaped plate *9* between the sides of which is welded a bar 10 to provide an enclosed stack gas passage *p* above the bar. The supporting rods 2 enter the space between the sides of the U-plate 9 below the bar 10 and may be

secured to the sides of the plate by rivets or pins 11. The pins 11 are preferably countersunk in such manner that the opposite faces of the plate 9 are smooth, inasmuch as these faces are flush with the opposite side faces of the connected heating wall.

Assuming that the first described form of beam assembly be employed, the ends of the bars *a* of the respective beam assemblies 3 are provided with notches 5^a for receiving two rows of spacer links 5. As shown, each spacer link, except the end ones, are arranged within the notches 5^a of two adjacent beams *a*, the upper row being arranged in staggered relation with respect to the lower row, and these spacer links are flat bars provided with T-heads at their opposite ends. They are made short enough not to interfere with each other when the heating walls 1 are pushed together to their minimum distance apart, but long enough to permit the heating walls to be pulled apart slightly. This operation may be effected by pulling on the two outside or end spacer links until the T-heads at the opposite ends of all the links between the end links are brought into tight engagement with the sides of the beams *a*, so that there will result a uniform wider spacing 5^b between the respective heating walls 1. When the heating walls are in their extreme contracted position, only one T-head of each spacer link will engage the side face of a beam *a* and the other T-head will be spaced a distance 5^c from other side of the beam *a*. The contracted relation of the spacer links and supporting beams is illustrated in Figs. 6 and 7.

The beam assemblies 3 and their respective heating walls are supported by hangers 6 located at the opposite ends of the beam assemblies and hooked over into circular notches cut out in the tops of the side supporting girder 7 (see Fig. 3). The notches permit the hangers 6 to swing in either direction as the heating walls are either pulled apart or pushed together. At their lower ends, the hangers 6 are fitted onto the cylindrical ends *a'* of the beams *a*, being held in place by pins 8.

When the form of supporting beam assembly involving the plate 9 is employed, and in which beams corresponding to the beams *a* are omitted, a plate may be welded to each end of the beam plate 9. This plate may be a short beam section provided, like the beam *a*, with notches for receiving the spacer links 5 and with a cylindrical or turned end for the mounting of the lower end of the hanger 6.

Fitted over the bars *a* at the opposite ends of each beam assembly 3 are notched plates 12 (Figs. 1, 3, 4 and 6), which serve not only as spacers to fix the minimum distance between the heating walls when they are

shoved together, but also as closures for the opposite ends of the cooling gas circulating channels p . These plates 12 may be welded to the opposite ends of their respective beam assemblies and may be provided with ports to which gas circulating pipes 13 are connected. The gas circulating pipes 13 on the opposite sides of the beam assemblies may be connected with the supply headers 14 that extend parallel with the supporting girders. One header 14 may act as the supply header for the cooling gas and the other as the exhaust header for receiving the gas discharged from the channels p .

15 At each end of the chamber A interposed between the end heating wall and the refractory surrounding wall B, is a frame constituted of vertical pipes 15, fitted at their upper ends into hollow castings 17 and at their bottoms into hollow castings 18. The lower ends of the pipes 15 may be interconnected and braced by a horizontal pipe 16 and their upper ends supplied with cooling gas from the stack gas header 14 by means 20 of the supply pipes 20. The pipe frame thus constituted, is supported at the top by the castings 17 which are connected to the beam assembly 3 of the contiguous end heating wall. Intermediate castings 21 and 25 surround the frame pipes between the top and bottom castings just mentioned, thereby providing a substantially continuous supporting surface for the end heating wall to rest against, so that the heating walls are 30 prevented from buckling or swinging outwardly, as the carbonaceous material between them seeks its angle of repose.

As shown in Figs. 4 and 5 the outside spacer links 23 of each series 5 are formed 40 at their inner ends with T-heads similar to the T-heads of the inside spacer links 5, but at their outer ends are provided with eyelets 23^a which are pivotally connected to the operating links 24. In turn, the latter are 45 pivoted to the inner ends of the pull rods 25. At their outer ends, the pull rods 25 are formed with bearings which receive a transverse horizontal shaft or rod 26, said shaft 26 extending through the pair of pull 50 rods 25 which are located at the opposite sides of the furnace, but at the same end thereof. With this construction, when the two shafts 26 at the opposite ends of the furnace, are moved away from each other, 55 a like motion will be transmitted to the outside spacer links 23 to pull apart the spacer links 5 as far as their key-heads will permit such motion, so that the heating walls 1 will also be pulled apart to effect a uniformly 60 wider spacing between such walls.

In order to hold the above described pipe frame rigidly in place and to prevent outward buckling or movement of the heating walls 1 when they are pushed together, 65 pusher rods 27 are pivotally connected to the frame castings 22. These pusher rods 27 pass through sleeves 96 set in holes in the refractory walls B and are dimensioned of larger diameter than the pusher rods 27 to afford plenty of clearance for permitting the 70 pusher rods to move vertically in their respective sleeves. A closure plate 97 fits snugly around each pusher rod and makes contact with the outer vertical surface of the corresponding sleeve to prevent escape of 75 gases from the interior of the furnace. At their outer ends, the pusher rods are provided with bearings for a transverse shaft 28, which, when moved inwardly, imparts a like motion to the several pusher rods, thereby holding the heating walls in their contracted position. The shaft 28 and its connected pusher rods 27 do not play any active part in the operation of retracting the heating walls, this being effected by the links 23, 24, 25 and shaft 26, but acts principally to prevent accidental outward displacement 80 of the heating walls from their contracted position.

According to the present embodiment of 85 the invention, a toggle mechanism is employed to move the shafts 26 at the opposite ends of the furnace outwardly and concurrently the shafts 28 to permit such movement and allow the shafts 26 with their connected parts to retract the heating walls into their uniformly wider spaced positions. The pulling rods 25 extend through snug bearings 33 secured to the transverse girders 34, inasmuch as the links 24 permit the slight 90 vertical movement incident to the outward movement of the pipe frames 15. Journalized on the puller shafts 26 at the opposite ends of the furnace structure are fittings 31 which are socketed to receive the lower ends of the 95 operating levers 29. These operating levers are inclined upwardly and toward the transverse central plane of the furnace structure, as shown especially in Figs. 1 and 2. At their upper ends the operating levers 29 enter socketed fittings 35, the latter being pivotally connected to socketed fittings 37 mounted on the opposite ends respectively of a horizontal connecting strut 39. Socketed fittings 32 are also journalized on the 100 shafts 28 and support the lower ends of inwardly and upwardly inclined levers 30. The upper ends of these levers 30 enter socketed fittings 36, the latter being in turn 105 pivotally connected to socketed fittings 38 mounted at the opposite ends of a second strut 40. Vertical pipes 41 connect the top strut fittings 37 with the bottom strut fittings 38. The top strut fittings 37 at both ends of the furnace are provided with racks 110 37^a which respectively mesh with pinions 43 mounted on the longitudinally extending driving shafts 44. The shafts 44 are provided with driven bevel gears 48 in mesh 115 with driving bevel gears 47 on a transverse 120

power shaft 46, the latter having a sprocket rigidly together. The nut 61 and screw drive 45.

With the above described construction, when power is applied to the sprocket 45, the drive shafts 44, through the gearing just mentioned, will rotate the pinions 43 to drive the racks 37^a either upwardly or downwardly in unison, depending on the direction of drive. If the racks 37^a are moved upwardly the operating levers 29 and 30 will be drawn inwardly towards the transverse central plane of the furnace to push the heating walls together. Reverse movement of the racks 37^a pushes out the operating levers 29 and 30 to retract the pipe frames 15, and this movement will be transmitted to the spacer links 5 to pull the heating walls apart into their uniformly wider spaced positions. During the movement of the parts in either direction, the vertical connecting pipes 41 shift vertically on supporting rods 42 which extend within said pipes. These rods 42 are secured at their lower ends to brackets mounted on the refractory walls of the furnace and at their upper ends to the rail supports, as shown more particularly in Fig. 3.

In accordance with the invention, provision is also made whereby the side walls within the chamber A may be retracted from the opposite ends of the heating walls 1, before the latter are retracted, in order to break any bond which may have been formed between the side walls and the coke between the heating walls, thereby permitting the heating walls to move apart readily for the pushing operation. The side walls S are constructed of pipe frame constituted of the end vertical pipes 51 and the connecting horizontal pipes 52, the latter being preferably welded at their ends into said end pipes 51. The end vertical pipes 51 are provided at their tops with pipe caps 50 to which are pivotally mounted the lower ends of the hangers 49. These hangers 49 extend upwardly to and hooked over the girders 7. Welded at intervals to each pair of horizontal pipes 52 are connecting vertical bars 58, said bars 58 constituting the anchors for the cast iron wall plates 59. As shown in Figs. 8 and 9 the wall plates 59 are rigidly secured to the anchors 58 by bolts 60 having T-heads, which when turned into vertical position may be passed through vertical slots 64 in the anchors 58. After the bolts have been inserted in the slots 64, so that the T-head is clear of the outer face of the anchor, the bolt may be turned so that the T-head lies in a horizontal position within the retaining Z-bar member 65, the latter preventing the T-head of the bolt from assuming a vertical position and becoming loose. The screw threaded end of the bolt is positioned within a socket provided on the inner face of the wall plate 59 and a nut 61 may be applied to said end of the bolt to secure the parts

rigidly together. The nut 61 and screw threaded end of the bolt lie wholly within the recess or socket, so that the inner surface of the wall plate 59 will be entirely flush and smooth. Lugs 62 and 63 projecting from the outer face of each plate 59 engage the top surfaces of the upper and lower horizontal pipes 52 and assist in keeping the plates 59 in rigid vertical alignment with respect to their supporting anchors 58.

Secured to the end pipes 51 of the respective opposite side walls S are castings 53, which are socketed to receive the inner ends of inwardly extending pipes 54. The outer ends of these pipes 54 are connected to the longitudinal horizontal pipe beams 55. Connected with the pipes 54 are nipples 56 through which cooling stack gases or other cooling media may be circulated into the vertical pipes 51 and connected horizontal pipes 52, for the purpose of keeping the pipe frame of the side walls S cool. The cooling gases or other media enter the vertical pipes 51 through the ports 57 and are subsequently distributed by said vertical pipes to the horizontal pipes 52.

Pivots secured to the upper and lower horizontal pipe beams 55 on both sides of the furnace are the inwardly and upwardly inclining levers 66. These levers 66, when drawn inwardly or pushed outwardly, by mechanism to be presently described, act either to push the opposite side walls S in unison towards the ends of the heating walls to close the latter and form enclosures for the intervening coking spaces or retorting spaces, or to pull the opposite side walls S away from the ends of the heating walls. The operation of the side walls is effected by the same mechanism that operates the bottom doors to permit the discharge of the finished coke.

The construction of the bottom doors T is somewhat similar to the side doors. Each bottom door is constituted of a frame made up of pipes 67 secured at their opposite ends to the end castings 68, the latter being keyed at their hinge ends on the longitudinal pipe shafts 69. These shafts 69 constitute the hinges for the doors T and are supported in sleeves 70 at the opposite ends of the furnace. Stack gases may be admitted through the ends of the pipe shafts 69 and thence circulated through the hollow castings 68 into the pipes 67 to keep the bottom door frames cool. The passage clear through the pipe shafts 69 may be blocked by a plug 71 (Fig. 4) which acts as a baffle to enforce the circulation just described.

The pipes 67 of the bottom door frame are tied together at intervals by anchors 72 similar to the anchors 58 of the side door frame and the bottom door plates 74 and 75 are secured to the corresponding anchors 72 by similarly recessed bolts 73. In

opening, the bottom doors T move away from each other as indicated by the dotted lines in Fig. 3; and, in closing, move upwardly toward each other to the full line position. In order to provide a tight closure at the meeting edges of the bottom doors, one of said doors may have its plate 75 flanged downwardly so that the meeting edge of the plate 74 of the other door will 10 overlap said flanged portion.

The hinge shafts 69 pass through and are keyed to the door operating levers 76, the latter being in turn pivotally connected to levers 77. These levers 77 have their opposite ends connected with fittings 78 attached to the lower ends of pipes 79. Secured to the upper ends of the pipes 79 are racks 80. The pipes 79 slide on inner rods 81 which are attached at their upper ends to the supporting girders and at their lower ends to suitable supporting brackets. The said racks 80 mesh with pinions 82 on shafts 83. The operating shafts 83 are furthermore provided with bevel gears 87 (Fig. 1) 20 in mesh with bevel gears 86 on the drive shaft 85. This shaft 85 may be driven by a sprocket 84. When the shafts 85 are turned in one direction by said sprocket 84, the gearing just described will draw the pipes 79 upwardly and operate the levers 77, 76 to close the bottom doors T. Reverse rotation of the sprocket 84 will lower the pipes 79 to open the bottom doors.

The retracting movement of the side doors 35 S takes place concurrently with the opening movement of the bottom doors T; vice versa, the pulling together of said side doors is effected concurrently with the closing movement of the bottom doors. This is 40 accomplished from the same driving mechanism that operates the bottom doors. As shown, the pipes 79 pass through fittings 88 and 89 to which the side door operating levers 66 are connected. Collars 90 and 91 45 are rigidly attached to the vertical pipes 79. Consequently when the racks 80 travel downwardly to open the bottom doors the collar 91 will engage the lowermost fitting 89 to move the latter downwardly and at the same time the upper arm 80^a of rack 80 50 will engage the uppermost fitting 88 thereby operating the toggles formed by the levers 66 and the fittings 88 and 89 to pull the side doors away from the ends of the heating walls. When the rack is travelling upwardly 55 during the movement of closing the bottom doors, the fittings 91^a will engage the underside of the fittings 89 and at the same time the collars 90 will engage the under- 60 side of the fittings 88, to operate the toggle in the reverse direction and push the side walls against the ends of the heating walls. By the time the heating walls have been 65 restored to such positions, the bottom doors 66 will be entirely closed.

In the operation of the furnace above described, the bottom doors are maintained in their open position and the side walls in their retracted position during the heating up stage. Hot gases may enter the chamber A through the heat ducts 92 and passing downwardly between the heating walls 1, said gases may exhaust through the bottom ducts 93. If desired, the flow of gases may be reversed so that the hot gases will enter 75 through the bottom ports 93 and pass out through the top ports 92. During the heating up operation, the heating walls 1 are retained in their narrow spaced position, in order to restrict as much as possible the 80 flow of hot gases between them and thus hasten the heating effect. The charging and pusher apparatus is not illustrated in the accompanying drawings and may be of any preferred form, such as the type of 85 charging and pushing apparatus shown and described in my before mentioned application Serial No. 535,791. While the heating up is being carried on, it will be found convenient to fill the charging trough. After 90 the walls 1 have been heated to the required coking temperature the bottom doors T are closed and the side walls S are pushed against the ends of the heating walls by the mechanism previously described. The 95 charging apparatus is then operated to remove the top door D from the chamber A and the retorts between the heating walls 1 are charged with the coal to be coked.

At the completion of the coking operation, 100 the bottom doors are opened and the side walls are retracted. Then the heating walls 1 are retracted to their uniformly wider spaced position and the pushing machine is operated to push the coke from between 105 the heating walls 1 downwardly into the coke car E, the inclined bottom doors serving as guides for directing the coke into the car. It is preferable that the rams of the pusher machine fit the spaces between 110 the heating walls when the latter are in their uniformly retracted position. After the coke has been pushed the top door D is replaced and a further heating up stage 115 is begun.

During the coking period, it will be found expedient to remove the coke car through the door 95, dump the coke, and return the empty car to the bottom of the furnace to receive the next charge. The 120 distillates which arise from the coal during the coking period may pass out through the ducts 92, which are at this time disconnected from the stack or from the supply of heating gases.

Preferably, the griders 34 and 7 form a water seal with the top door or cover D to prevent the waste of distillate or heating gases.

By the invention, the distillation of car- 130

bonaceous material is carried on at a very rapid rate. The heat is applied to the same surfaces, from which it is subsequently transferred to the coal. The heating walls are of 5 very cheap material and large numbers of them may be employed. When distilling coal, the coke produced in accordance with the present invention separates readily from the surfaces of the heating walls, the troubles 10 arising from sticking of the coke in low temperature distillations heretofore practiced being practically eliminated.

The invention as hereinbefore set forth may be variously embodied within the scope 15 of the claims hereinafter made.

I claim:

1. Apparatus for distilling carbonaceous materials embodying: a plurality of spaced relatively movable heating walls; link mechanism connecting said walls for retracting the latter into uniformly wider spaced positions or for pushing them together into their relatively narrower spaced positions; spacer means interposed between said walls for 20 limiting their movement toward each other; toggle mechanism operatively connected with said walls and acting through said link mechanism to move the walls into either of said positions, said toggle mechanism including means for preventing accidental movement of said walls out of their narrower spaced positions; movable side walls for closing the spaces between the ends of said heating walls; toggle mechanism for moving said 25 side walls either toward or away from the ends of said heating walls; bottom door means for closing the bottoms of the retorts formed by the spaces between the heating walls; and toggle mechanism for opening or closing said bottom door means; substantially as specified.

2. Apparatus for distilling carbonaceous

45 materials embodying: a plurality of spaced relatively movable heating walls; link mechanism connecting said walls for retracting the latter into uniformly wider spaced positions or for pushing them together into their 50 relatively narrower spaced positions; toggle mechanism operatively connected with said walls and acting through said link mechanism to move the walls into either of said positions, said toggle mechanism including 55 means for preventing accidental movement of said walls out of their narrower spaced positions; movable side walls for closing the spaces between the ends of said heating walls; toggle mechanism for moving said 60 side walls either toward or away from the ends of said heating walls; bottom door means for closing the bottoms of the retorts formed by the spaces between the heating walls; and toggle mechanism for opening or closing said bottom door means; and a unitary 65

driving mechanism for said side wall toggle mechanism and said bottom door toggle mechanism; substantially as specified.

3. Apparatus for distilling carbonaceous materials embodying: a plurality of spaced 70 relatively movable heating walls; link mechanism connecting said walls for retracting the latter into uniformly wider spaced positions or for pushing them together into their relatively narrower spaced positions; toggle mechanism operatively connected with said walls and acting through said link mechanism to move the walls into either of said 75 positions, said toggle mechanism including means for preventing accidental movement of said walls out of their narrower spaced positions; movable side walls for closing the spaces between the ends of said heating walls; toggle mechanism for moving said 80 side walls either toward or away from the ends of said heating walls; bottom door means for closing the bottoms of the retorts formed by the spaces between the heating walls; and toggle mechanism for opening or closing said bottom door means; substantially as specified.

4. Apparatus for distilling carbonaceous materials embodying: a plurality of spaced relatively movable heating walls; link mechanism connecting said walls for retracting the latter into uniformly wider spaced positions or for pushing them together into their relatively narrower spaced positions; spacer means interposed between said walls for 85 limiting their movement toward each other; toggle mechanism operatively connected with said walls and acting through said link mechanism to move the walls into either of said positions; movable side walls for closing the spaces between the ends of said heating walls; toggle mechanism for moving said side walls either toward or away from the ends of said heating walls; bottom door means for closing the bottoms of the retorts formed by the 90 spaces between the heating walls; and toggle mechanism for opening or closing said bottom door means; and a unitary driving mechanism for said side wall toggle mechanism and said bottom door toggle mechanism; substantially as specified.

5. Apparatus for distilling carbonaceous materials embodying: a plurality of spaced relatively movable heating walls; link mechanism connecting said walls for retracting the latter into uniformly wider spaced positions or for pushing them together into their relatively narrower spaced positions; toggle mechanism operatively connected with said walls and acting through said link mechanism to move the walls into either of said positions; movable side walls for closing the spaces between the ends of said heating walls; toggle mechanism for moving said side walls either toward or away from the ends of said heating walls; bottom door means for closing the bottoms of the retorts formed by the spaces between the heating walls; and toggle mechanism for moving said side walls either toward or

away from the ends of said heating walls; bottom door means for closing the bottoms of the retorts formed by the spaces between the heating walls; and toggle mechanism for opening or closing said bottom door means; substantially as specified.

6. Apparatus for distilling carbonaceous materials embodying: a plurality of spaced relatively movable heating walls; link mechanism connecting said walls for retracting the latter into uniformly wider spaced positions or for pushing them together into their relatively narrower spaced positions; spacer means interposed between said walls for limiting their movement toward each other; movable side walls for closing the spaces between the ends of said heating walls; means for moving said side walls either toward or away from the ends of said heating walls; bottom door means for closing the bottoms of the retorts formed by the spaces between the heating walls; and means for opening or closing said bottom door means; substantially as specified.

7. Apparatus for distilling carbonaceous materials embodying: a plurality of spaced relatively movable heating walls; means for retracting the latter in unison into uniformly wider spaced positions or for pushing them together into their relatively narrower spaced positions; spacer means interposed between said walls for limiting their movement toward each other; means for preventing accidental movement of said walls out of their narrower spaced positions; movable side walls for closing the spaces between the ends of said heating walls; means for moving said side walls either toward or away from the ends of said heating walls; bottom door means for closing the bottoms of the retorts formed by the spaces between the heating walls; and means for opening or closing said bottom door means; substantially as specified.

8. Apparatus for distilling carbonaceous materials embodying: a plurality of spaced relatively movable heating walls; means for retracting the latter in unison into uniformly wider spaced positions or for pushing them together into their relatively narrower spaced positions; means for preventing accidental movement of said walls out of their narrower spaced positions; movable side walls for closing the spaces between the ends of said heating walls; means for moving said side walls either toward or away from the ends of said heating walls; bottom door means for closing the bottoms of the retorts formed by the spaces between the heating walls; and means for opening or

closing said bottom door means; substantially as specified.

9. Apparatus for distilling carbonaceous materials embodying: a plurality of spaced relatively movable heating walls; means for retracting the latter in unison into uniformly wider spaced positions or for pushing them together into their relatively narrower spaced positions; spacer means interposed between said walls for limiting their movement toward each other; movable side walls for closing the spaces between the ends of said heating walls; means for moving said side walls either toward or away from the ends of said heating walls; bottom door means for closing the bottoms of the retorts formed by the spaces between the heating walls; and means for opening or closing said bottom door means; substantially as specified.

10. Apparatus for distilling carbonaceous materials embodying: a plurality of spaced relatively movable heating walls; means for retracting the latter in unison into uniformly wider spaced positions or for pushing them together into their relatively narrower spaced positions; movable side walls for closing the spaces between the ends of said heating walls; means for moving said side walls either toward or away from the ends of said heating walls; bottom door means for closing the bottoms of the retorts formed by the spaces between the heating walls; and means for opening or closing said bottom door means; substantially as specified.

11. Apparatus for distilling carbonaceous materials embodying: a plurality of spaced relatively movable heating walls; means for retracting the latter into uniformly wider spaced positions or for pushing them together into their relatively narrower spaced positions; movable side walls for closing the spaces between the ends of said heating walls; means for moving said side walls either toward or away from the ends of said heating walls; bottom door means for closing the bottoms of the retorts formed by the spaces between the heating walls; and means for opening or closing said bottom door means; substantially as specified.

12. In an apparatus for distilling carbonaceous materials, in combination: a plurality of spaced relatively movable heating walls; link mechanism connecting said walls for retracting the latter into uniformly wider spaced positions or for pushing them together into their relatively narrower spaced positions; spacer means interposed between said walls for limiting their movement toward each other; and toggle mechanism operatively connected with said walls and acting through said link mechanism to move the walls into either of said posi-

- tions, said toggle mechanism including means for preventing accidental movement of said walls out of their narrower spaced positions; substantially as specified.
13. Apparatus for distilling carbonaceous materials embodying: a plurality of spaced relatively movable vertical parallel heating walls; movable side walls for closing the spaces between the ends of said heating walls; and bottom door means for closing the bottoms of the retorts formed by the spaces between the heating walls; substantially as specified.
14. Apparatus for distilling carbonaceous materials embodying: a plurality of spaced relatively movable parallel heating walls; movable side walls for closing the spaces between the ends of said heating walls; and bottom door means for closing the bottoms of the retorts formed by the spaces between the heating walls; substantially as specified.
15. Apparatus for distilling carbonaceous materials embodying: a plurality of spaced relatively movable vertical heating walls; movable side walls for closing the spaces between the ends of said heating walls; and bottom door means for closing the bottoms of the retorts formed by the spaces between the heating walls; substantially as specified.
16. Apparatus for distilling carbonaceous materials embodying: a plurality of spaced relatively movable heating walls; movable side walls for closing the spaces between the ends of said heating walls; and bottom door means for closing the bottoms of the retorts formed by the spaces between the heating walls; substantially as specified.
17. In an apparatus for distilling carbonaceous materials, in combination: a series of heating walls in position side by side spaced and relatively movable from each other in a direction substantially normal to each wall of said series; link mechanism connecting said walls together for shifting the walls of the series severally in said direction into wider spaced positions or for shifting the walls of the series severally into their relatively narrower spaced positions; and toggle mechanism operatively connected with said walls and acting through said link mechanism to move the walls into either of said positions, said toggle mechanism including means for preventing the end walls of said series from moving farther apart out of their closer position relative to each other; substantially as specified.
18. In an apparatus for distilling carbonaceous materials, in combination: a plurality of spaced relatively movable heating walls; link mechanism connecting said walls for retracting the latter into uniformly wider spaced positions or for pushing them together into their relatively narrower spaced positions, spacer means interposed between said walls for limiting their movement toward each other; and toggle mechanism operatively connected with said walls and acting through said link mechanism to move the walls into either of said positions; substantially as specified.
19. In an apparatus for distilling carbonaceous materials, in combination: a series of heating walls in position side by side spaced and relatively movable from each other in a direction substantially normal to each wall of said series; link mechanism connecting said walls together for shifting the walls of the series severally in said direction into wider spaced positions or for shifting the walls of the series severally into their relatively narrower spaced positions; and toggle mechanism operatively connected with said walls and acting through said link mechanism to move the walls into either of said positions; substantially as specified.
20. The method of carbonizing carbonaceous materials which consists in storing heat in a plurality of substantially parallel spaced vertical walls, then feeding the material to be distilled into the spaces between said walls and therein carbonizing said material by transferring heat previously stored in said walls directly to said material; and retracting said walls into uniformly relatively wider spaced positions to facilitate discharge of said material; substantially as specified.
21. In an apparatus for distilling carbonaceous materials, in combination: a plurality of spaced relatively movable heating walls; means for retracting the latter into uniformly wider spaced positions or for pushing them together into their relatively narrower spaced positions; spacer means interposed between said walls for limiting their movement toward each other; and means for preventing accidental movement of said walls out of their narrower spaced positions; substantially as specified.
22. The method of carbonizing carbonaceous materials which consists in storing heat in a plurality of substantially parallel spaced vertical walls, then feeding the material to be distilled into the spaces between said walls and therein carbonizing said material by transferring heat previously stored in said walls directly to said material; and retracting said walls into relatively wider spaced positions to facilitate discharge of said material; substantially as specified.
23. In an apparatus for distilling carbonaceous materials, in combination: a series of heating walls in position side by side spaced and relatively movable from each other in a direction substantially normal to each wall of said series; means for shifting the walls of the series severally in said direction into wider spaced positions or for shifting the walls of the series severally into

their relatively narrower spaced positions; and means for preventing the end walls of said series from moving farther apart out of their closer position relative to each other; substantially as specified.

24. In an apparatus for distilling carbonaceous materials, in combination: a plurality of spaced relatively movable heating walls; means for retracting the latter into uniformly wider spaced positions or for pushing them together into their relatively narrower spaced positions; and spacer means interposed between said walls for limiting their movement toward each other; substantially as specified.

25. In an apparatus for distilling carbonaceous materials, in combination: a series of at least three heating walls in position side by side spaced and relatively movable from each other in a direction substantially normal to each wall of said series; and means for shifting the walls of the series severally in said direction into wider spaced positions or for shifting the walls of the

series severally into their relatively narrower spaced positions; substantially as specified.

26. In an apparatus for distilling carbonaceous materials, in combination: a series of at least three heating walls in position side by side spaced and relatively movable from each other in a direction substantially normal to each wall of said series; and means for shifting the walls of the series severally in said direction into wider spaced positions to facilitate discharge of the treated materials; substantially as specified.

27. The method of distilling carbonaceous material, which consists in: charging such material into spaces between relatively movable heating walls, distilling the material, then increasing the spaces between said walls to discharge the residue, and moving said walls into their original spaced relation; substantially as specified.

In testimony whereof I have hereunto set my hand.

FRANZ PUENING.
